UNITED STATES PATENT OFFICE.

SYDNEY A. BECK, OF BURLINGAME, CALIFORNIA, ASSIGNOR TO HOOVER SPRING COMPANY, OF SAN FRANCISCO, CALIFORNIA, A CORPORATION OF CALIFORNIA.

BUMPER-ATTACHING DEVICE.

1,381,901.

Specification of Letters Patent. Patented June 21, 1921.

Application filed February 14, 1921. Serial No. 444,670.

To all whom it may concern:

Be it known that I, SYDNEY A. BECK, a citizen of the United States of America, residing at Burlingame, in the county of San Mateo and State of California, have invented certain new and useful Improvements in Bumper-Attaching Devices, of which the following is a specification, reference being had to the accompanying drawings.

10 This invention relates to improvements in contrivances for adjustably mounting fenders or bumpers on automobiles, and particularly to improvements in devices by means of which bumper-attaching irons are fastened to the frame of the car so as to be readily adjusted in place. An object of this invention is to provide a mechanism of the character described hereinbefore, which will prove simple in construction, comparatively 15 cheap in manufacture and low in cost of installation and repair, and efficient and durable in operation and use.

In the drawings illustrating the principle of this invention and the best mode now 20 known to me of applying that principle, Figure 1 is an elevation of so much of the frame or chassis of an automobile and of a bumper-attaching iron secured thereto, as is necessary to illustrate this invention; Fig. 2 is a plan of what is shown in Fig. 1; Fig. 3 is a section on the line 3—3 of Fig. 1, looking in the direction of the arrows; and Fig. 4 is a detail that illustrates in front elevation the hanger-block for an attaching-iron.

25 As is best shown in Fig. 3, the chassis or frame member *a* (only a fragment of which is shown) is of the channel-iron type comprising a web *b*, upper flange *c*, and lower flange *c'*. The hook-end *d'* of a hook-bolt *d* is engaged with the lower flange *c'* of the chassis *a* and the body or shank of the bolt *d* passes thereunder.

Against the outer lateral face of the web *b* of the channeled frame-member *a*, there 40 lies the recessed lateral face *e'* of the hanger-block *e*, from the lower end of which projects laterally a perforated boss or ear *e''*, which extends under the lower flange *c'* and through which passes the threaded end 45 of the shank of the hook-bolt *d*. A nut *d''* is screwed on the threaded extremity of the latter and serves to fasten together the frame-member *a*, the hanger-block *e* and the hook-bolt *d*.

50 55 The face *e'* of the hanger-block *e* is formed

with a lengthwise-extending recess *f*, the bottom wall of which is formed with a longitudinal slot *f'* and each of the lateral walls of which is formed with a vertical series of notches *f''*. The polygonal or faced head 60 *g'* of a bolt *g* engages with the walls of a pair of these notches *f''* opposed to each other, and the bolt *g* is, in this manner, prevented from turning while its head *g'* is thus engaged. The shank of the bolt *g* passes 65 through the slot *f'* and a hole formed in the inner end of the bumper-attaching iron *h*. Neither the other or outer end of the latter nor the bumper thereby carried is shown in the drawings. A nut *g''* is screwed 70 on the projecting threaded extremity of the bolt *g* and serves to fasten the bumper-attaching iron *h* to the hanger-block *e*. The vertical series of notches *f''* permit the position of the bolt *g* to be adjusted along the 75 longitudinal slot *f'* and the inner end of the bumper-attaching iron *h* to be shifted from and toward the lower end of the hanger-block *e* along the outer face thereof, so that the bumper is kept level by this adjustment, 80 when the bumper is attached to chassis or frames having different pitches. Moreover, by means of the construction just described, it has been found entirely feasible to do away with the use of bends in the inner ends 85 of the bumper-attaching irons, and to use bumper-attaching irons or arms *h* the inner ends of which are straight.

The inner extremity *h'* of the attaching-iron *h* may be fastened in any suitable manner to the chassis, as by means of a bolt passing through a snubber-hole (not shown) in the chassis, or by means of a hook-bolt *i* the threaded end of the shank of which passes through a hole in the inner extremity *h'* and is engaged by a nut *i'*. A spacing-block *j* is interposed between the inner extremity *h'* and the frame-member *a*.

In accordance with the patent statute, I have hereinbefore described the preferred 100 form of this invention; but I realize that changes may be made therein without departing from the spirit of this invention, and I desire to be understood as regarding such changes as falling within the scope of the 105 claims that follow hereinafter. For example, the hanger-block *e* may be used near the end *h'* of the iron *h*, and the spacing-block *j* will then preferably be shifted into the position now shown as being occupied 110

by the hanger-block *e*. In case a snubber is used, the snubber-bolt may be passed through the chassis *a* and the iron *h*, in order to fasten these parts together at the snubber. 5 When the snubber is not used, a cap-screw is passed through the snubber-hole, in the chassis, and the iron *h*.

I claim:

1. Means for adjustably mounting bumpers on automobile-frames, including a hanger-block secured to the automobile-frame; a fastening device for securing the hanger-block to the automobile-frame; a bumper-attaching iron free from engagement by the fastening device and freely movable up and down along the hanger-block; and means for securing the bumper-attaching iron to the hanger-block when the iron is in the position desired. 15
2. Means for adjustably mounting bumpers on automobile-frames, including a hanger-block secured to the automobile-frame; a fastening device for securing the hanger-block to the automobile-frame; a bumper-attaching iron free from engagement by the fastening device and freely movable up and down along the hanger-block; and means mounted in the slot for securing the bumper-attaching iron to the hanger-block when the iron is in the position desired. 20

ers on automobile-frames including a slotted hanger-block secured to the automobile frame; a fastening device for securing the hanger-block to the automobile-frame; a bumper-attaching iron free from engagement by the fastening device and freely movable up and down along the slot in the hanger-block; and means mounted in the slot for securing the bumper-attaching iron to the hanger-block when the iron is in the 25 position desired.

Signed at the city and county of San Francisco, in the State of California, in the presence of the two undersigned witnesses, this 7th day of February, A. D. 1921.

SYDNEY A. BECK.
